CRIMPING TOOL

Harold B. Martin, 1020 Sheridan Ave., Roselle, N.J., and
Daniel P. Schwester, 45 Fulton St., East Orange, N.J.

Filed Sept. 28, 1960, Ser. No. 62,291

Term of patent 14 years

(Cl. D54—13)

FIGURE 1 is a perspective view of a crimping tool showing our new design;

FIGURE 2 is a side elevational view of the crimping tool shown in FIGURE 1; and

FIGURE 3 is a top plan view in elevation of the same.

The opposite side of the crimping tool not shown is substantially a mirror image of the side of the tool shown.

The dominant features of our design for the crimping tool disclosed, reside in the portions shown in full lines.

We claim:

The ornamental design for a crimping tool, as shown and described.
